APPARATUS FOR UPSETTING THE ENDS OF
PACKAGES OF YARNAllen H. Lloyd, Milford, Ohio, assignor to Gaston
County Dyeing Machine Company, Stanley,
N. C., a corporation of North Carolina

Application January 12, 1951, Serial No. 205,788

9 Claims. (Cl. 18-8)

1

This invention relates to textile machinery and more especially to an apparatus for upsetting, breaking or crimping yarn which is to be subjected to sizing and dyeing operations after the yarn has been wound into tubular packages or cakes which are usually cylindrically-shaped. However, it often happens that the turns of yarn which are wound adjacent opposed ends of the cylindrically-shaped packages or cakes are placed under greater tension than the yarn wound about the medial portion of the package. It is evident that sizing solutions or dyes would more easily penetrate fibers of yarns which are wound loosely than fibers of yarns which are wound tightly at opposed ends of the packages of yarn and it often happens that the turns of yarn forming the opposed ends of the cylindrically-shaped or conically-shaped packages would not be fully penetrated by the dyes or sizing solutions with the result that the yarn in each package is not dyed or treated uniformly throughout its length which, in many instances, would necessitate discarding the same.

It is, therefore, the primary object of this invention to provide apparatus for upsetting opposed ends of cylindrically or conically-shaped packages of yarn so as to relieve the tension in the yarns at the outer edges of and at the opposed ends of each package so the packages may subsequently be subjected to a dyeing, sizing or any other treating operation wherein the dye or other solution will penetrate the fibers of the yarn in each package uniformly throughout the package.

It is another object of this invention to provide an apparatus for automatically breaking the opposed ends of cones of yarn which apparatus has at least one pair of cup-shaped members adapted to fit over the opposed ends of a cone of yarn, whereby cones of yarn may be moved successively between said cup-shaped members and said apparatus also being provided with means automatically operable to cause said cup-shaped members to move toward each other to compress or break the ends of the cone of yarn disposed therebetween and also having means for releasing said cone of yarn from between said cup-shaped members after compression.

It is another object of this invention to provide a machine for automatically upsetting, breaking or crimping opposed ends of packages of yarn which comprises a lower continuously moving conveyor and an upper continuously moving conveyor which moves in synchronization with the lower conveyor and each of the con-

veyors having a plurality of spaced cup-shaped members or dies thereon having concave faces on the side thereof remote from the conveyor. The lower conveyor preferably extends a substantial distance beyond the upper conveyor and each of the dies or cup-shaped members has a spindle extending outwardly from the center of the concave face thereof which is adapted to receive a tubular package of yarn. Then packages of yarn are successively placed on the cup-shaped members on the lower conveyor and the packages of yarn pass beneath the upper conveyor and the coinciding cup-shaped members on the upper conveyor engage the upper ends of the packages of yarn under pressure to thus cause the turns of yarn at opposed ends of the packages to be rolled upon each other thus upsetting the same and relaxing the tension thereon. It is evident that the conveyors necessarily converge slightly towards each other from the point at which the packages are first engaged by the cup-shaped members on the upper conveyor to where the packages move out of range of the upper conveyor, to thus cause the pressure to be applied to opposed ends of the packages gradually.

It is another object of this invention to provide apparatus of the type described and which is adjustable to accommodate packages of yarns of varying size.

Some of the objects of the invention having been stated, other objects will appear as the description proceeds when taken in connection with the accompanying drawings in which—

Figure 1 is a side elevation of the machine showing the same operating upon a plurality of packages of yarn;

Figure 2 is an enlarged fragmentary side elevation showing one of the dies associated with the lower conveyor, with parts in section;

Figure 3 is a top plan view of the machine looking down from the top of Figure 1;

Figure 4 is an elevation with parts in section looking substantially along the line 4—4 in Figure 1;

Figure 5 is a side elevation of the machine looking at the opposite side thereof from that shown in Figure 1 but omitting the cup-shaped members and yarn packages for purposes of clarity;

Figure 6 is an end elevation looking at the right-hand end of Figure 1 with the upper portion thereof being broken away;

Figure 7 is an enlarged fragmentary elevation 55 of one of the cup-shaped members associated

with the corresponding conveyor chain and showing a package of yarn in association therewith, and being taken looking substantially along the line 7-7 in Figure 3;

Figure 8 is a fragmentary vertical sectional view looking substantially along the line 8-8 in Figure 6 but showing the lower end of the corresponding package as it is forced into the die to upset the lower end thereof.

Referring more specifically to the drawings, the numeral 10 broadly designates the frame of the machine which comprises spaced transverse frame members 11 and 12 which are shown in the form of angle bars, and each of which may be provided with a plate 13 secured at the lower end thereof as by welding. These transverse frame members 11 and 12 are adapted to be secured to a floor F or the like by any suitable means such as bolts 14 which penetrate the angle bars 11 and 12 and also penetrate the plates 13.

A pair of upstanding transversely-spaced frame members in the form of angle bars 15 and 16 are welded at their lower ends intermediate the ends of the horizontally disposed frame member 11 and are bridged at their upper ends by a horizontally disposed frame member 17. At the rear or left-hand end of the machine, in Figure 1, a pair of upstanding frame members 21 and 22, in the form of angle bars are welded at their lower ends intermediate the ends of the rear transverse frame member 12 and these frame members 21 and 22 extend upwardly.

The rear ends of horizontally disposed frame members 23 and 24 are welded to the respective vertically disposed frame members 21 and 22. The horizontally disposed frame members 23 and 24 are spaced upwardly from the lower ends of the frame members 21 and 22, respectively, and extend forwardly substantially beyond the vertically disposed frame members 15 and 16 and are suitably secured at their front ends, as by welding, intermediate the upper and lower ends of respective vertically disposed frame members 25 and 26. The lower end of each of the frame members 25 and 26 has a plate 27 suitably secured thereto, as by welding, which is penetrated by suitable bolts 28 for securing the same to the floor.

The upper ends of the vertically disposed front end frame members 25 and 26 are bridged by a horizontally disposed frame member 31 which is cut away, as at 32 (Figure 3), to provide clearance for the cup-shaped members on the lower conveyor to be later described. The vertically disposed front end frame members 25 and 26 are bridged intermediate their ends by a horizontally disposed frame member 33, the frame members 31 and 33 being welded at opposed ends thereof to the vertically disposed frame members 25 and 26.

Welded to the upper ends of the vertically disposed frame members 25 and 26 are the ends of a pair of lower conveyor support frame members 34 and 35 which are shown in the form of angle bars which extend upwardly and rearwardly at an angle and are welded intermediate their ends to the vertically disposed side frame members 15 and 16 and are welded at their other or rear ends to the vertically disposed side frame members 21 and 22. The angularly disposed lower conveyor support members 34 and 35 are bridged by a plurality of spaced transverse frame members 36 to the upper surfaces of each of which a pair of spaced substantially vertically disposed track support members 37 and 38 are welded,

the upper ends of the respective track support members 37 and 38 serving to support trackways or tracks 41 and 42 (Figures 1 and 5) which are shown in the form of angle bars which slidably support the upper reaches of respective conveyor chains 43 and 44 of a lower conveyor broadly designated at 45.

The conveyor chains 43 and 44 are mounted at the front of the machine on respective sprocket wheels 46 and 47 which are fixedly mounted on a common shaft 50 which is rotatably mounted in bearing blocks 51 of a suitable take-up mechanism broadly designated at 52. Each take-up mechanism 52 may comprise a substantially inverted U-shaped member 53 suitably secured to the corresponding angularly disposed lower conveyor support members 34 and 35 as by bolts 54. Each U-shaped member 53 has opposed ends of a threaded shaft 55 rotatably mounted therein which shafts threadably penetrate the corresponding bearing block 51 and opposed ends of which project beyond the members 53 and are adapted to be engaged by a suitable hand tool for rotating the threaded shaft 55 and to thus vary the relative position of the bearing blocks 51 for taking up slack in the conveyor chains 43 and 44. Any suitable conveyor take-up mechanism may be used if desired.

The conveyor chains 43 and 44 extend longitudinally of the machine and are supported by the tracks 41 and 42 and are mounted at the rear of the machine on respective sprocket wheels 69 and 61 which are fixedly mounted on a horizontally disposed lower conveyor drive shaft 62 rotatably mounted in bearing blocks 63 secured to the respective vertically disposed frame members 20 and 21 by any suitable means such as bolts 64 (Figure 1).

Referring to Figure 5, it will be observed that the lower conveyor drive shaft 62 also has a sprocket wheel 66 fixedly mounted at one end thereof on which a sprocket chain 67 is mounted. The sprocket chain 67 extends downwardly and forwardly at an angle and its lower portion is mounted on a sprocket wheel fixedly mounted on a reducer output shaft 70 which extends from a suitable speed reducer 71. This speed reducer may be of a type such as is manufactured by Boston Gear Works of Boston, Massachusetts, and such as is shown in their catalogue No. 54 on page 213 and which is known as a Type U Boston Reductor. It is evident that there are many different types of speed reducers which may be employed in the capacity of the reducer 71 shown in Figures 1 and 2, and the reducer 71 is shown for purposes of illustration only.

This reducer 71 also has an input shaft 72 thereon on which a pair of V-pulleys 73 are fixedly mounted. Suitable V-belts 74 are mounted on the pulleys 73 and extend inwardly on the apparatus and are also mounted on coinciding pulleys 75 fixedly mounted on a motor shaft 76 of a suitable electric motor 77. The electric motor 77 has a suitable cable 80 connected thereto and extending therefrom to a manually operable electric switch 81 suitably secured on a portion of the frame, such as the vertically disposed side frame member 15, and from which another cable 82 extends, the cable 82 has wires 83 and 84 therein which extend to a suitable source of electrical energy, not shown.

The reducer 71 is secured by any suitable means, such as screws 86 (Figure 5), to a drive unit support plate 85 welded to the upper surfaces of the longitudinally extending frame mem-

bers 23 and 24. The electric motor 77 is suitably secured, as by bolts 87 (Figure 6) to the upper surface of a motor support plate 90 which is pivoted at one end thereof, as at 91, on the drive unit support plate 85 and the end of the plate 90 remote from the pivot point 91 is slidably penetrated by an adjustment bolt 92 which also slidably penetrates a block 93 projecting outwardly from and being welded to the drive unit support plate 85. The plate 90 is held in a raised position at its end remote from the pivot point 91 by the V-belts 74 extending between the pulleys 73 and 75 and the bolt 92 is tightened or loosened to increase or decrease the tension in the V-belts 74 as desired.

The lower conveyor chains 43 and 44 support suitable dies or cup-shaped members, each of which is broadly designated at 100 and each being substantially annular or circularly-shaped and being provided with a substantially hemispherical or concave cavity 101 therein (Figures 2, 7 and 8). The cup-shaped members or dies 100 may be of any desired size to accommodate any desired size of cone and for purposes of illustration, the dies shown in Figures 3, 4 and 6 are shown as being of a larger size than the dies shown in Figure 1.

Referring to Figures 2, 7 and 8, it will be observed that the outer surface of each of the dies 100 is substantially convex and has a projection 102 extending from the lower surface thereof and has lateral projections 103 on opposed sides thereof which are provided with substantially triangularly-shaped depending portions 104 at the outer ends thereof which, as shown in Figure 2, are adapted to extend between adjacent rollers 105 of each of the conveyor sprocket chains 43 and 44, the purpose of which will be presently described.

Each of the lower conveyor chains 43 and 44 is provided with a plurality of special spaced links 106 which extend outwardly substantially from the respective conveyor chains 43 and 44. Each of the projections 103 on each of the dies 100 is provided with a recess or notch 107 in which the outwardly extending portion of the special link 106 is adapted to fit. The link 106 is slidably penetrated by a screw 110 which is threadably embedded in the corresponding projection 103 for securing the respective dies 100 to the lower conveyor chains 43 and 44. It might be stated that, although the screws 110 serve in securing the respective dies 100 to the conveyor chains 43 and 44, the dies 100 may pivot slightly on the respective screws 110. Thus, the projections 104 are provided on each of the outwardly projecting portions 103 of the dies 100 to permit a limited amount of pivotal movement of the respective dies relative to the conveyor chains 43 and 44 and these projections 104 engage the adjacent rollers 105 of the conveyor chains 43 and 44 to permit but limit pivotal movement of the dies 100. The reason for permitting this pivotal movement of the dies 100 will be later described.

Now, each of the dies 100 is adapted to support a package or cone of yarn indicated at P, the particular packages of yarn illustrated having a plurality of turns of yarn wound about a tube 112 of substantially the same length as that of the package P, it being well known to those familiar with the art that substantially all packages of yarn are wound about a tube such as the tube 112 or on a cone or other similar member. Therefore, each of the dies 100 is provided with a cavity 113 which is disposed in the bottom of the hemi-

spherical cavity 101 and which is provided as a flat-bottomed receptacle against which the lower end of a pilot pin or spindle 114 may be supported.

The pilot pin 114 is held in the cavity 113 by any suitable means such as a screw 115 which slidably penetrates the projection 102 at the bottom of the die 100 and is threadably embedded in the lower end of the corresponding pilot pin 114. The pilot pin 114 is preferably rounded at its upper end, as at 116, so that it may easily enter the tube 112 as the package of yarn P is placed thereon by an operator. It will be observed in Figure 8 that the cavity 113 is substantially larger than the pin 114 to accommodate pins of larger diameter than the pin 114 since the internal diameter of the tubes 112 may vary from, say, $\frac{1}{8}$ of an inch in diameter to as much as $\frac{1}{2}$ inches in diameter and, thus, the pilot pin 114 may be replaced by pins of a different diameter in accordance with the size of the tubes in the cones or packages of yarn being processed. It will be observed that the pilot pin 114 preferably extends substantially above the upper edge of the die or cup-shaped member 100 in Figure 8 so as to be readily accessible to the operator and to facilitate the placing of a tube 112 thereover.

It is thus seen that as the lower conveyor moves about the sprocket wheels in the manner described, packages of yarn may be placed in the dies 100 at the intake at front of the machine and be carried rearwardly or to the left in Figure 1. As the packages P move through the machine they are compressed in a manner to be described.

Upper conveyor

There is also provided an upper conveyor broadly designated at 120 which comprises a pair of endless sprocket conveyor chains 121 and 122 spaced transversely of the machine and these conveyor chains 121 and 122 support a plurality of second dies, each of which is designated broadly at 123. The dies 123 are identical to the first-named dies 100 and are mounted on the respective upper conveyor chains 121 and 122 in the same manner in which the dies 100 are mounted on the lower conveyor chains 43 and 44.

Since the upper or second cup-shaped members or dies 123 are substantially identical to the lower cup-shaped members or dies 100, the same reference characters shall apply to those parts of the dies 123 which are identical to the dies 100 with the prime notation added. It might be stated that the pilot pins 114' in the dies 123 should preferably be of substantially less length relative to the dies 123 than the pins 114 in the dies 100 since they are only employed in centering the upper end of the package of yarn in the die 123 as it moves along with the lower reaches of the upper conveyor chains 121 and 122. Also, if the pilot pins 114' in the upper die 123 were of the same relative length as the pilot pins 114, they would probably enter the package of yarn to one side of the tube 112 as a result of which the corresponding package of yarn P would not be positioned in axial alignment with the center of the corresponding dies 100 and 123.

The upper conveyor chains 121 and 122 are mounted at the rear of the machine on respective sprocket wheels 124 and 125 which are fixedly mounted on a horizontally disposed idler shaft 126 rotatably mounted at opposed ends thereof in bearing blocks 51' which are parts of take-up mechanisms broadly designated at 52', these take-

up mechanisms 52' being identical to the take-up mechanism 52 except being of lesser length and bearing the same reference characters with the prime notation added and a further description thereof is deemed unnecessary. The take-up mechanisms 52' are secured to the rear ends of substantially horizontally disposed upper conveyor support frame members 130 and 131 which extend forwardly and terminate adjacent the corresponding vertically disposed frame members 15 and 16. The frame members 130 and 131 each has a bearing block 132 suitably secured to the upper surface thereof as by bolts 133, these bearing blocks 132 being mounted on a transverse upper conveyor drive shaft 134.

The upper conveyor drive shaft 134 is rotatably mounted at opposed ends thereof in bearing blocks 135, there being one of these bearing blocks suitably secured to the inner surface of each of the vertically disposed frame members 15 and 16, by any suitable means such as bolts 136. It will be observed, in Figures 3 and 5, that the upper conveyor drive shaft 134 extends substantially beyond the outer surface of the vertically disposed frame member 16 and has a sprocket wheel 137 fixed thereon on which a sprocket chain 140 is mounted. This sprocket chain 140 extends downwardly and is mounted on a sprocket wheel 141 fixed on a shaft 142. The shaft 142 is rotatably mounted in bearing blocks 143 suitably secured, as by bolts 144, to the upper surfaces of the lower conveyor support members 34 and 35.

It will be observed in Figures 3, 4 and 6 that the shaft 142 also has a sprocket wheel 146 fixed thereon, the lower portion of which is engaged by the upper reach of a sprocket chain 147 (Figure 5). The upper portion of the sprocket chain 147 is mounted on a sprocket wheel 150 rotatably mounted on a stub shaft 151 fixedly mounted in a block 152 suitably secured to the rear surface of the vertically disposed side frame member 16. The sprocket chain extends downwardly and rearwardly in Figure 5 and is also mounted on a sprocket wheel 154 fixed on the shaft 70 extending from the speed reducer 71 heretofore described.

It is thus seen that the electric motor drives the speed reducer 71 which in turn transmits rotation to the output shaft 70 and this shaft 70, in turn, causes the upper reaches of the lower conveyor to move from right to left in Figure 1 or from left to right in Figure 5 and causes the lower reaches of the upper sprocket chains 121 and 122 to also move in the same direction in synchronization with the lower conveyor chains 43 and 44.

The upper conveyor frame members 130 and 131 are pivotally supported at their front ends on the shaft 134 and they are adjustable at their rear ends. There is provided an angle bar 157 which bridges and is welded to the upper surfaces of the upper conveyor support members 130 and 131 and extends substantially on each side of the same as is clearly shown in Figure 3. This member 157 has the upper ends of a pair of adjustment rods 158 and 159 suitably secured thereto, as by welding, which extend downwardly and slidably penetrate the upper flanges of the corresponding lower conveyor support members 34 and 35 and each of which has adjustment nuts 160 threadably mounted thereon and bearing against the upper and lower surfaces of the horizontal flanges of the respective frame members 34 and 35 to thus permit adjustment of the upper conveyor support members 130 and 131 to vary the distance between the lower reaches of the upper conveyor

75

chains 121 and 122 and the upper reaches of the lower conveyor chains 43 and 44 to permit packages of yarn of varying size to be compressed by this machine.

It will be observed in Figure 1 that the rear vertically disposed frame member 20 is graduated, as at 162, and a substantially L-shaped pointer 163 is adapted to move adjacent the graduations 162 with movement of the upper conveyor support frame members 130 and 131 to serve as a guide or reference to the operator of the machine in determining the relative position of the rear portion of the conveyor chains 121, 122 and 43, 44. The point 163 is suitably secured, as by welding, to the outer surface of the upper conveyor support member 130.

The upper conveyor support members 130 and 131 have a plurality of longitudinally spaced track frame members 165 and 166 depending therefrom and suitably secured thereto, as by welding, and to the lower ends of which a plurality of transverse track support members 167 are suitably secured as by welding. The track support frame members 167 extend transversely of the machine and support a pair of transversely spaced tracks or trackways 170 and 171 against which the upper surfaces of the lower reaches of the upper conveyor chains 121 and 122, respectively, are adapted to move in sliding engagement therewith.

Upon movement of the conveyors 45 and 120 from right to left in Figure 1, the cup-shaped members 123 will gradually engage the upper end of the package of yarn in the coinciding lower cup-shaped member 100 and will gradually exert an increasing pressure thereon until the opposed ends of the packages of yarn have been rolled toward each other at their outer edges substantially in the manner in which the package of yarn is shown at the extreme left-hand portion of Figure 1. Due to the fact that the upper and lower cup-shaped members 123 and 100, respectively, are not always disposed in axial alignment with each other as they cooperate in acting upon opposed ends of a package of yarn, the cup-shaped members 100 and 123 will be caused to pivot upon their respective screws 110 and 110', this pivotal movement permitting the coinciding cup-shaped members 100 and 123 to substantially align themselves with one another and the projections 104 thereon limiting the amount of pivotal movement which may occur due to the projections 104 engaging one or the other of the adjacent rollers 105 (Figure 2) on the corresponding conveyor chain. This pivotal movement is limited so as to prevent the dies 100 and 123 from swinging excessively as the axes thereof are disposed in a substantially horizontal plane, as would be the case adjacent the outer surfaces of the corresponding sprocket wheels on which the lower and upper respective conveyor chains 121, 122 and 43, 44 are mounted.

It is evident that the packages which have been placed on the dies 100 will slide off of the pilot pins 114 and 114' as the dies 100 move to inverted position, in which position they are shown on the lower reaches of the lower conveyor chains 43 and 44 in Figures 1 and 5.

It is thus seen that there is provided a machine for upsetting or breaking the outer portions of opposed ends of packages of yarn automatically comprising an upper and a lower conveyor, the lower conveyor projecting substantially beyond the upper conveyor so as to permit an operator to place packages of yarn on the dies

provided therefor on the lower conveyor. This results in all of the packages of yarn which are of substantially the same length having opposed ends thereof upset uniformly so as to loosen the turns of yarn at opposed ends and at the outer edges of each package of yarn so that all of the yarn in each package of yarn may be uniformly penetrated by the dyes, sizing solutions or other treating fluids to which the packages of yarn may be subsequently subjected.

Various changes in the particular structure illustrated in the drawings can be made without departing from the spirit of the invention or the scope of the accompanying claims. For example, the dies or cup-shaped members could be disposed so as to move toward each other in a horizontal rather than a vertical plane.

In the drawings and specification there has been set forth a preferred embodiment of the invention and although specific terms are employed, they are used in a generic and descriptive sense only and not for purposes of limitation, the scope of the invention being defined in the claims.

I claim:

1. An apparatus for upsetting opposed ends of a tubular package of yarn comprising a plurality of first dies provided with concave upper surfaces and each having a pilot pin projecting outwardly from the center thereof onto which a package of yarn may be placed, a first conveyor means to which the first dies are connected for moving the dies past a predetermined point, a plurality of second dies having concave lower surfaces disposed substantially above the first dies, a second conveyor means to which the second dies are connected for moving the second dies in unison with the first dies past said predetermined point, pressure applying means associated with the first and the second dies and being effective at said predetermined point to cause the dies to move relative to each other, whereby upon a package of yarn being placed in each of said first dies, said second dies will cause pressure to be exerted on opposed ends of each package as it moves past said predetermined point to thereby upset the opposed ends and outer edges thereof.

2. An apparatus for upsetting opposed ends of a tubular package of yarn comprising a plurality of first dies provided with concave upper surfaces and each having a pilot pin projecting outwardly from the center thereof onto which a package of yarn may be placed, a first conveyor means to which the first dies are connected for moving the dies past a predetermined point, a plurality of second dies having concave lower surfaces disposed substantially above the first dies, a second conveyor means to which the second dies are connected for moving the second dies in unison with the first dies past said predetermined point, each of said second dies also having a pilot pin therein to assist in positioning the corresponding end of each package admitted thereto concentrically therewith.

3. An apparatus for upsetting opposed ends of a tubular package of yarn comprising a plurality of first dies provided with concave upper surfaces and each having a pilot pin projecting outwardly from the center thereof onto which a package of yarn may be placed, a first conveyor means to which the first dies are connected for moving the dies past a predetermined point, a plurality of second dies having concave lower surfaces disposed substantially above the first

dies, a second conveyor means to which the second dies are connected for moving the second dies in unison with the first dies past said predetermined point, pressure applying means associated with the first and the second dies and being effective at said predetermined point to cause the dies to move relative to each other, whereby upon a package of yarn being placed in each of said first dies, said second dies will cause pressure to be exerted on opposed ends of each package as it moves past said predetermined point to thereby upset the opposed ends and outer edges thereof and a connection between the conveyors and the corresponding dies permitting a predetermined amount of pivotal movement of the dies relative to each other so the dies may be self-aligning with respect to each other upon a package of yarn being engaged at opposed ends thereof by the coinciding first and second dies.

4. An apparatus for upsetting opposed ends of tubular packages of yarn comprising a plurality of first dies provided with concave upper surfaces and each having a pilot pin projecting outwardly from the center thereof onto which a package of yarn may be placed, a first conveyor means to which the first dies are connected for moving the dies past a predetermined point, a plurality of second dies having concave lower surfaces disposed substantially above the first dies, a second conveyor means to which the second dies are connected for moving the second conveyor means to which the second dies are connected for moving the second dies in unison with the first dies past said predetermined point, each of said second dies also having a pilot pin therein to assist in positioning the corresponding end of each package admitted thereto concentrically therewith, pressure applying means associated with the first and the second dies and being effective at said predetermined point to cause the dies to move relative to each other, whereby upon a package of yarn being placed in each of said first dies, said second dies will cause pressure to be exerted on opposed ends of each package as it moves past said predetermined point to thereby upset the opposed ends and outer edges thereof, and a connection between the conveyors and the corresponding dies permitting a predetermined amount of pivotal movement of the dies relative to each other so the dies may be self-aligning with respect to each other upon a package of yarn being engaged at opposed ends thereof by the coinciding first and second dies.

5. A machine for upsetting opposed ends of tubular packages of yarn comprising a frame, a lower conveyor mounted in the frame comprising a pair of endless sprocket roller chains, driving means for imparting movement to the pair of sprocket roller chains, each of the sprocket roller chains having special links thereon spaced substantially from each other, a plurality of substantially cup-shaped dies pivotally connected to the special links and being disposed between the two chains, substantially triangular projections on the cup-shaped members having the pointed ends thereof extending between adjacent rollers on the roller chains and being adapted to engage adjacent rollers upon the corresponding cup-shaped members being pivoted to limit pivotal movement thereof, each of the cup-shaped members having a substantially concave cavity in its outer surface relative to the roller chains and also having a pilot pin projecting outwardly from the center of said cavity and onto which

11

a tubular package of yarn is adapted to be placed, a second conveyor of identical construction to that of the first conveyor disposed substantially above the first conveyor and being of substantially less strength than the first conveyor, said second conveyor also including a pair of transversely spaced conveyor chains and also having a plurality of substantially cup-shaped members supported thereby, means for driving the second conveyor in synchronization with the first conveyor, the first and second conveyors being disposed in converging relation to each other in the direction of travel of the conveyor, means for adjusting the displacement between the conveyors at the ends thereof towards which the conveyors are driven whereby, an operator may place a package of yarn in each of the cup-shaped members on the lower conveyor in advance of the cup-shaped members moving beneath the upper conveyor and whereby the cup-shaped members on the upper conveyor will engage the upper ends of the packages of yarn carried by the cup-shaped members on the lower conveyor and, due to the convergence of the conveyors, a gradual pressure will be applied to opposed ends of the packages of yarn to thus roll the turns of yarn at the outer edges of each package of yarn over one another to thus upset the ends of the packages of yarn automatically.

6. A machine for upsetting opposed ends of tubular packages of yarn comprising a frame, a lower conveyor mounted in the frame comprising a pair of endless sprocket roller chains, driving means for imparting movement to the pair of sprocket roller chains, each of the sprocket roller chains having special links thereon spaced substantially from each other, a plurality of substantially cup-shaped dies pivotally connected to the special links and being disposed between the two chains, substantially triangular projections on the cup-shaped members having the pointed ends thereof extending between adjacent rollers on the roller chains and being adapted to engage adjacent rollers upon the corresponding cup-shaped members being pivoted to limit pivotal movement thereof, each of the cup-shaped members having a substantially concave cavity in its outer surface relative to the roller chains and also having a pilot pin projecting outwardly from the center of said cavity and onto which a tubular package of yarn is adapted to be placed, a second conveyor of identical construction to that of the first conveyor disposed substantially above the first conveyor and being of substantially less length than the first conveyor, said second conveyor also including a pair of transversely spaced conveyor chains and also having a plurality of substantially cup-shaped members supported thereby, means for driving the second conveyor in synchronization with the first conveyor, the first and second conveyors being disposed in converging relation to each other in the direction of travel of the conveyors, means for adjusting the displacement between the conveyors at the ends thereof towards which the conveyors are driven whereby, an operator may place a package of yarn in each of the cup-shaped members on the lower conveyor in advance of the cup-shaped members moving beneath the upper conveyor and whereby the cup-shaped members on the upper conveyor will engage the upper ends of the packages of yarn carried by the cup-shaped members on the lower conveyor and, due to the convergence of the conveyors, a gradual pressure will be applied to opposed ends of the packages of yarn to thus roll the turns of yarn at the outer edges of each package of yarn over one another to thus upset the ends of the packages of yarn automatically.

12

be applied to opposed ends of the packages of yarn to thus roll the turns of yarn at the outer edges of each package of yarn over one another to thus upset the ends of the packages of yarn automatically and said cup-shaped members on the lower conveyor being inverted after the yarn package thereon has been compressed to permit the package to fall free thereof.

7. A machine for upsetting opposed ends of tubular packages of yarn comprising a frame, a lower conveyor mounted in the frame comprising a pair of endless sprocket roller chains, driving means for imparting movement to the pair of sprocket roller chains, each of the sprocket roller chains having special links thereon spaced substantially from each other, a plurality of substantially cup-shaped dies pivotally connected to the special links and being disposed between the two chains, substantially triangular projections on the cup-shaped members having the pointed ends thereof extending between adjacent rollers on the roller chains and being adapted to engage adjacent rollers upon the corresponding cup-shaped members being pivoted to limit pivotal movement thereof, each of the cup-shaped members having a substantially concave cavity in its outer surface relative to the roller chains and also having a pilot pin projecting outwardly from the center of said cavity and onto which a tubular package of yarn is adapted to be placed, a second conveyor of identical construction to that of the first conveyor disposed substantially above the first conveyor and being of substantially less length than the first conveyor, said second conveyor also including a pair of transversely spaced conveyor chains and also having a plurality of substantially cup-shaped members supported thereby, means for driving the conveyors, the first and second conveyors being disposed in converging relation to each other in the direction of travel of the conveyors whereby, an operator may place a package of yarn in each of the cup-shaped members on the lower conveyor in advance of the cup-shaped members moving beneath the upper conveyor and whereby the cup-shaped members on the upper conveyor will engage the upper ends of the packages of yarn carried by the cup-shaped members on the lower conveyor and, due to the convergence of the conveyors, a gradual pressure will be applied to opposed ends of the packages of yarn to thus roll the turns of yarn at the outer edges of each package of yarn over one another to thus upset the ends of the packages of yarn automatically.

8. A machine for upsetting opposed ends of tubular packages of yarn comprising a frame, a lower conveyor mounted in the frame comprising a pair of endless sprocket roller chains, driving means for imparting movement to the pair of sprocket roller chains, each of the sprocket roller chains having special links thereon spaced substantially from each other, a plurality of substantially cup-shaped dies pivotally connected to the special links and being disposed between the two chains, substantially triangular projections on the cup-shaped members having the pointed ends thereof extending between adjacent rollers on the roller chains and being adapted to engage adjacent rollers upon the corresponding cup-shaped members being pivoted to limit pivotal movement thereof, each of the cup-shaped members having a substantially concave cavity in its outer surface relative to the roller chains and also having a pilot pin projecting outwardly from the center of said cavity and onto which a tubu-

lar package of yarn is adapted to be placed, a second conveyor of identical construction to that of the first conveyor disposed substantially above the first conveyor and being of substantially less length than the first conveyor, said second conveyor also including a pair of transversely spaced conveyor chains and also having a plurality of substantially cup-shaped members supported thereby, each of said dies in the upper conveyor also having a pilot pin projecting from the center thereof terminating substantially short of the outer edge of the dye and which is adapted to enter the tubular package of yarn as each package of yarn passes into engagement with the coinciding cup-shaped member on the second conveyor, means for driving the second conveyor in synchronization with the first conveyor, the first and second conveyors being disposed in converging relation to each other in the direction of travel of the conveyors, means for adjusting the displacement between the conveyors at the ends thereof towards which the conveyors are driven whereby, an operator may place a package of yarn in each of the cup-shaped members on the lower conveyor in advance of the cup-shaped members moving beneath the upper conveyor and whereby the cup-shaped members on the upper conveyor will engage the upper ends of the packages of yarn carried by the cup-shaped members on the lower conveyor and, due to the convergence of the conveyors, a gradual pressure will be applied to opposed ends of the packages of yarn to thus roll the turns of yarn at the outer edges of each package of yarn over one another to thus upset the ends of the packages of yarn automatically.

9. A machine for upsetting opposed ends of tubular packages of yarn comprising a frame, a lower conveyor mounted in the frame comprising a pair of endless sprocket roller chains, driving means for imparting movement to the pair of sprocket roller chains, each of the sprocket roller chains having special links thereon spaced substantially from each other, a plurality of substantially cup-shaped dies pivotally connected to the special links and being disposed between the two chains, substantially triangular projections on the cup-shaped members having the pointed ends thereof extending between adjacent rollers on the roller chains and being adapted to engage adjacent rollers upon the corresponding cup-shaped members being pivoted to limit pivotal movement thereof, each of the cup-shaped members having a substantially concave cavity in its outer surface relative to the roller chains and

also having a pilot pin projecting outwardly from the center of said cavity and onto which a tubular package of yarn is adapted to be placed, a second conveyor of identical construction to that of the first conveyor disposed substantially above the first conveyor and being of substantially less length than the first conveyor, said second conveyor also including a pair of transversely spaced conveyor chains and also having a plurality of substantially cup-shaped members supported thereby, each of said dies in the upper conveyor also having a pilot pin projecting from the center thereof terminating substantially short of the outer edge of the dye and which is adapted to enter the tubular package of yarn as each package of yarn passes into engagement with the coinciding cup-shaped member on the second conveyor, means for driving the second conveyor in synchronization with the first conveyor, the first and second conveyors being disposed in converging relation to each other in the direction of travel of the conveyors, means for adjusting the displacement between the conveyors at the ends thereof towards which the conveyors are driven whereby, an operator may place a package of yarn in each of the cup-shaped members on the lower conveyor in advance of the cup-shaped members moving beneath the upper conveyor and whereby the cup-shaped members on the upper conveyor will engage the upper ends of the packages of yarn carried by the cup-shaped members on the lower conveyor and, due to the convergence of the conveyors, a gradual pressure will be applied to opposed ends of the packages of yarn to thus roll the turns of yarn at the outer edges of each package of yarn over one another to thus upset the ends of the packages of yarn automatically and said cup-shaped members on the lower conveyor being inverted after the yarn package thereon has been compressed to permit the package to fall free thereof.
